US0D1111086S

(12) **United States Design Patent** (10) Patent No.: **US D1,111,086 S**
(45) Date of Patent: ** Feb. 3, 2026

(54) **MUSICAL INSTRUMENT AUDIO INTERFACE DEVICE**

(71) Applicant: **Fender Musical Instruments Corporation**, Los Angeles, CA (US)

(72) Inventors: **James Matisán Gifford**, Tempe, AZ (US); **Brian Ramey**, Mesa, AZ (US)

(73) Assignee: **Fender Musical Instruments Corporation**, Los Angeles, CA (US)

(**) Term: **15 Years**

(21) Appl. No.: **29/970,804**

(22) Filed: **Oct. 30, 2024**

(51) LOC (15) Cl. **17-99**

(52) U.S. Cl.

USPC **D17/99**; D14/188

(58) **Field of Classification Search**

USPC D17/99; D14/188, 203.1, 203.3

CPC G10H 1/0066; G10D 99/00

See application file for complete search history.

(57) **CLAIM**

The ornamental design for a musical instrument audio interface device as shown and described.

DESCRIPTION

FIG. 1 is a first top perspective view of a musical instrument audio interface device showing our new design;

FIG. 2 is a second top perspective view thereof;

FIG. 3 is a top view thereof;

FIG. 4 is a bottom view thereof;

FIG. 5 is a side view thereof;

FIG. 6 is a side view of a side opposite that of FIG. 5;

FIG. 7 is a front view thereof; and,

FIG. 8 is a rear view thereof.

The broken lines shown in the drawings illustrate portions of the musical instrument audio interface device that form no part of the claimed design.

1 Claim, 6 Drawing Sheets
